UNITED STATES PATENT OFFICE.

WILL L. JONES, OF DOUGLAS, ARIZONA, ASSIGNOR, BY MESNE ASSIGNMENTS, OF ONE-HALF TO W. E. MORRISON.

DEEP-WELL PUMP.

1,181,457.

Specification of Letters Patent.

Patented May 2, 1916.

Application filed April 26, 1915. Serial No. 23,902.

To all whom it may concern:

Be it known that I, WILL L. JONES, citizen of the United States, residing at Douglas, in the county of Cochise and State of 5 Arizona, have invented new and useful Improvements in Deep-Well Pumps, of which the following is a specification.

This invention relates to pumping mechanism for deep wells.

10 One object of the invention is to produce a simple and improved construction and arrangement of parts including a working barrel and plungers reciprocating therein in opposite directions to produce a steady or 15 constant flow, the construction being such that a foot valve may be dispensed with.

A further object of the invention is to 20 simplify and improve the construction of the plungers, each having a single valve and valve seat, thereby avoiding leakage which is liable to occur when a valve is provided which must simultaneously engage two seats.

25 A further object of the invention is to simplify and improve the general construction, arrangement and combination of parts constituting the invention.

With these and other ends in view which 30 will readily appear as the nature of the invention is better understood, the same consists in the improved construction and novel arrangement and combination of parts which will be hereinafter fully described and particularly pointed out in the claim.

35 In the accompanying drawing has been illustrated a simple and preferred form of the invention, it being, however, understood that no limitation is necessarily made to the precise structural details therein exhibited, 40 but that changes, alterations and modifications within the scope of the claim may be resorted to when desired.

In the drawing,—Figure 1 is a vertical 45 sectional view illustrating a portion of a well casing, a working barrel, the plungers operating therein, the solid and the tubular plunger stems, and the packing boxes through which said stems are guided. Fig. 50 2 is a vertical sectional view taken through one of the plungers, said view being on a larger scale. Fig. 3 is a transverse sectional view taken on the line 3—3 in Fig. 2. Fig. 4 is a transverse sectional view taken on the line 4—4 in Fig. 2.

Corresponding parts in the several figures 55 are denoted by like characters of reference.

The well casing 15 is provided at its upper end with a laterally extending discharge spout 16 and with a packing box 17 through which a tubular plunger stem 18 is guided, 60 said tubular plunger stem terminating at its upper end in a packing box 19 through which a second plunger stem 20 is guided. The plunger stem 20 has been shown as being of solid construction, but a tubular construction may be used, if desired, in which event, however, the lower end of said plunger stem should be obstructed, making it the equivalent of a solid construction.

The working barrel 21, which is suitably 70 supported at the lower end of the well casing, has an inlet 22, and within said barrel the upper and lower plungers 23 and 24 are arranged, said lower plunger being connected with and carried by the interior 75 plunger stem 20, while the exterior tubular plunger stem 18 carries the upper plunger 23. The plungers, which are mounted on the respective stems for limited sliding movement, are of identical construction, each 80 comprising an annular cylindrical body 25 having a valve seat 26 at its lower end and provided with inwardly extending radially disposed wings or ribs 27 having upwardly extending bolts 28. The valve rings 29 and 85 packing leathers or cups 30 are disposed in alternate order on the annular base and extend upwardly therefrom, the uppermost valve ring being provided with inwardly extending lugs 31 through which the bolts 90 28 extend, said bolts extending also through lugs 32 formed on the sleeve 33 which slidably engages the plunger stem, it being obvious that said sleeve is suitably proportioned to engage the inner or outer plunger 95 stem, as the case may be. The parts are assembled together by the nuts 34 which are threaded upon the bolts 28 and tightened against the flange 32 of the sleeve 33.

The inner and outer plunger stems are 100 equipped with valves 35, 36 adapted to engage the seats 26 of the plungers 23 and 24, respectively. The slideable movement of said plungers on their respective stems is limited by stop members which may be in the nature of flanges or collars 37, 38 fixed on the stems 20 and 18, respectively.

In operation, the stems 18, 20 may be re-

ciprocated in opposite directions by means of a pumping jack of suitable construction which, however, has not been illustrated, as it forms no part of the present invention.

5 When the inner stem 20 is moved downwardly, and the tubular stem 18 is moved upwardly, the valve of the lower plunger will be unseated, permitting fluid to move upwardly through the plunger body. The

10 valve of the upper plunger will be seated, causing fluid to be lifted by said upper plunger. When the movement is reversed, the valve of the upper plunger will be unseated, permitting upward flow through said upper plunger of liquid which is now forced upwardly or lifted by the action of the lower plunger, the valve of which is now seated. Each valve having but a single seat, there is no opportunity for unequal wear upon the

15 20 valve seats which in many devices at present in use results in leakage involving the loss of a great deal of time in making the necessary repairs. The packing boxes for the respective plunger stems are located at

25 the surface, and any leakage at these points may be quickly and effectually checked by

simply tightening the glands or repacking the boxes.

Having thus described the invention, what is claimed as new, is:—

30 A plunger comprising an annular base having a valve seat at its lower end and inwardly extending radial ribs provided with upwardly extending bolts, valve rings and leathers supported in alternate order on the base, the uppermost ring having inwardly extending lugs, a stem, a sleeve slidably engaging the stem and having outwardly extending lugs, said lugs and those of the uppermost valve ring being engaged 35 by the bolts, nuts on said bolts whereby the parts are assembled, a valve carried by the stem and engaging the seat formed on the base, and a stop member fixed on the stem to limit the slidable movement of the 40 plunger.

35 In testimony whereof I affix my signature in presence of two witnesses.

40 WILL L. JONES.
